DISHWASHING MACHINE

Lawrence A. Loeb, New Haven, Conn.

Application June 13, 1944, Serial No. 540,033

2 Claims. (Cl. 134—139)

1

This invention relates to dishwashing machines and more particularly to a household dishwashing machine of cabinet style which may be employed in the usual household kitchen.

It is contemplated by the present invention to provide a washing machine of improved construction and operation as compared to those in use at the present time. As illustrated and described, the improvements are applied to a dishwashing machine which will be controlled manually in that it will be provided with a control element moved manually to a plurality of stations or positions. For example, the handle or control member may normally stand in the "off" position, corresponding to that in which the machine is at rest. It may then be moved to the "fill" position in which hot and cold water inlets are opened and the drain closed, so that the tub or tank will be filled with the desired supply of water of the proper temperature. The handle may then be moved to the "on" position in which the dishwashing operation is effected. In the present instance, the washing of the dishes is accomplished by the recirculation of the water in the tank by a motor-driven pump. That is to say, the warm water is drawn from the tank by the pump and by means of a suitable sprayer sprayed over the dishes to cleanse them, the pump and spray jet taking the place of a rotor or agitator employed in the tank in some of the devices in use at the present time.

After the dishes have been cleansed, the control member may then be moved to the "rinse" position in which the drain is held in "closed" position and the hot water inlet alone opened to permit clean hot water to enter the tank for rinse purposes. During this time, an auxiliary or overflow drain, which is provided, will serve to prevent the water in the tank from rising above a predetermined level, the excess water being drawn from the bottom of the tank in order to drain from the latter principally the water used in the washing operation. During this rinse operation, the water in the tank will again be recirculated by the pump to effect the rinsing of the dishes. The control member may then be turned to "off" or original position after the rinsing position is finished, which will end the dishwashing cycle and the dishes may be removed from the machine and a new supply provided for a subsequent operation.

It is sometimes inconvenient in dishwashing machines in present use to place the dishes in and remove them from the dish rack within the tank, which rack is usually located near the bottom of the tank. In the present device, this

2

lower dish rack is movable so that it may be raised to an elevated position conveniently accessible to the operator. This raising of the dish rack is effected hydraulically by means of the same pump which recirculates the water in the tank, the arrangement being such that the outlet of the pump may be connected to the hydraulic lifting device to raise the latter, which would remain in raised position until a valve is operated to permit the venting of the lifting device and thus allow the rack to descend by its own weight.

There is also provided in the present device a soap-dispensing apparatus consisting of a soap container, which may be filled at intervals and which will be automatically operated by the movement of the control member or handle to discharge into the tank a proper supply of soap for one operation, whereby the operator, after placing the dishes in the rack while it is held in a raised position in the tank, needs only to lower the rack and then turn the handle or control member to the various positions in order to fill the tank with a supply of water of the proper temperature, admit a supply of soap to this water, wash the dishes by a spray jet from recirculation of the water in the tank, rinse the dishes while a spray of hot water is being admitted to the tank, then drain the tank, all by movement of the single control member.

30 One object of the present invention is the provision of a dishwashing machine of improved operation.

A still further object of the invention is to provide a rotating jet or spray head by means of which the water in the tank of the machine is recirculated and drawn over the dishes during the cleansing operation.

To these and other ends the invention relates to the novel features and combinations of parts 40 to be hereinafter described and claimed.

In the drawing:

Fig. 1 is a sectional view of a washing machine embodying my invention, certain parts being shown diagrammatically;

45 Fig. 2 is a sectional view on line 2—2 of Fig. 1;
Fig. 3 is a top plan view of the parts shown in Fig. 2;

Fig. 4 is a detail view of the motor control switch;

50 Fig. 5 is a sectional view on line 5—5 of Fig. 2;
Fig. 6 is a top plan view of the spray head at the lower portion of the tank;

Figs. 7, 8, 9 and 10 are diagrammatic views showing the positions of certain of the parts in 55 various stages in the operation of the machine;

Fig. 11 is a partial sectional view of the front portion of the machine showing the soap dispenser;

Fig. 12 is an enlarged sectional view on line 12-12 of Fig. 11;

Fig. 13 is a sectional view on line 13-13 of Fig. 11; and

Fig. 14 is a partial sectional view showing a modified form of dish rack raising means.

To illustrate a preferred embodiment of my invention I have shown a dishwashing machine comprising a cabinet 10 having mounted therein a tank 11, the tank being provided with a cover 12, which may be removed or opened to permit access to the interior of the tank for loading the dishes therein preparatory to a washing operation. It will be noted that the front or left end wall of the tank as shown in Fig. 1 is spaced from the front of the cabinet 10, and within this space is mounted a control panel 13 upon which is carried the control mechanism, as will be hereinafter described.

Projecting upwardly through the bottom of the tank and secured therein is a hollow standard 14 upon which is slidably mounted a tubular member 15 to the lower end of which are secured radial arms 15^a upon which is removably supported the lower dish rack, designated generally by the numeral 16. The standard 14 extends through the bottom 17 of the tank and may be suitably sealed against leakage as shown at 18.

The tank is provided with a drain 20, having at the upper portion thereof a well 21 in which is mounted the drain valve 22. This valve is provided with a stem 23, the lower end of which is connected to a lever 24, pivoted at 25, so that when this lever is oscillated in a vertical direction about its pivot, the valve 22 will be raised and lowered to open and close the drain. A spring 27 is secured at one end of the lever 24 and at its other end to a collar 28 on the drain pipe, which spring normally acts to hold the drain valve in open position, as shown in Fig. 1.

The tank is supplied with water by means of hot and cold water pipes 30 and 31, which lead to the usual domestic supplies of hot and cold water. These pipes are directed into valve casings 32 and 33, respectively, in each of which is mounted a valve 34 (only one of these valves being shown). Each of the valves 34 may be actuated by a lever 35 pivoted at 36 at one end, and having pivoted to the other end a link 37. To one of the links 37 is pivoted a lever 38 controlling the hot water valve, while to the link 37 of the cold water valve is pivoted a lever 38^a, so that the valves 34 will be controlled by movement of the levers 38 and 38^a. The levers 38 and 38^a are provided, respectively, with springs 39 and 39^a, these springs tending, as shown in Fig. 2, to hold the free ends of the levers downwardly and thus hold the valves 34 in closed position.

Pipes 42 and 43 lead from the valve casings 32 and 33, respectively, to a T 44 (Fig. 1) from which a pipe 45 leads to a spray head 46 upon the inner wall of the tank 11, this spray head being provided with a plurality of slotted openings 47 and 48. It will be noted that the opening 47 is substantially horizontally disposed, while the slot 48 is inclined downwardly. With this construction, the hot and cold water supplied to the tank will be mixed in the T 44 and will be supplied to the tank in a plurality of sprays or jets, one being directed downwardly toward the dishes in the rack 16 and the other being directed across the tank so as to strike the dishes upon the far side of the rack.

Within the tank 11 and adjacent the bottom thereof is rotatably mounted a spray head 50 of hollow formation and having provided on its upper surface a plurality of elongated openings 51 obliquely directed so as to cause the spray head to rotate when water under pressure is expelled through these openings. This spray head is rotatably mounted upon a collar 52 supported upon the bottom of the tank and which surrounds the standard 14 previously referred to. Water is delivered to the spray head through an inlet pipe 53, which pipe leads to a valve casing 54 having a rotary valve member 55 therein, the valve having a port 56 which connects the pipe 53 with a pipe 57 leading to the outlet of a pump 58 driven by a motor 59. The inlet of the pump is supplied through a pipe 60 leading to a port 61 in the valve 55, which in the position of the valve shown in Fig. 1 connects the pipe 60 to a pipe 62 leading to the well 21 at the bottom of the tank. It will be apparent that in this position of the valve and associated parts, when the motor 59 is in operation and the pump 58 is driven, water will be drawn from the tank 11 (the valve 22 presumably being closed) through the pipe 62 into the pump 58 and discharged through the pipe 57, and the pipe 53 into the spray head 50, which will be caused to rotate and throw jets of this water over the dishes in the tank to cleanse and rinse them, as this action takes place during both the washing or cleansing and rinsing operations.

Provision is made for rotating the valve 55 by means of a member 63 connected thereto, to which member is pivoted a link 64, this link as shown in Fig. 3 being connected at its upper end to a lever 65 pivoted to the cabinet at 66, which lever projects without the cabinet, as shown at 67, where it may be manually oscillated to move the link 64 in a vertical direction. The movement of the valve 55 may be limited by the pin 68 and slot 69.

Within the standard 14 is mounted a pipe 70 connected to a pipe 71 leading into the drain 20, the pipe 70 being sufficiently small to be spaced from the walls of the hollow standard 14, so that water may enter the interior of this standard around the pipe and be discharged into the upper end of the member 15. Between this latter member and the standard 14 is provided suitable packing 72 to confine this water above the upper end of the standard 14. With this construction, it will be apparent that when water is admitted to the standard 14 through a connection 73 at its lower end and a pipe 74 leading into the connection 73, the pressure of this water upon the upper closed end of the hollow member 15 will cause the latter to rise upon the standard 14 and carry with it the dish rack 16, so as to elevate the rack and bring it to a level near the top of the tank (the cover 12 being opened) so that it may be conveniently loaded with dishes. To prevent an excess of pressure in the member 15 a valve 75 is provided at the upper end of the pipe 70, which valve will be lifted from the mouth of this pipe by the chain 76 connected to the valve and to the upper closed end of the member 15, so that when the latter member reaches a point limited by the length of the chain 76, the valve 75 will be raised from its seat and permit the water in the upper end of the member 15 to drain downwardly through the pipe 70 into the drain 20 and prevent further raising of the dish rack.

As will be presently explained, the lowering of the dish rack is effected by venting the pipe 74

and permitting the parts to descend under their own weight.

The pipe 74 leads to a port 80 in valve 55 in the position of this valve shown in Fig. 1, and is by this port connected to a tube 81 leading into the drain 20. This is the position occupied when the member 15 is vented to the drain to allow the lowering of the dish rack. When, however, the valve 55 is moved in a clockwise direction as permitted by the pin 68 and slot 69, the outlet pipe 57 of the pump 58 will be connected by the valve port 56 to the pipe 74 leading into the standard 14. With the motor 59 and pump 58 in operation, in this last position of the parts, the water delivered by the pump through the pipe 57 will pass into the standard 14 and raise the rack 16. For this raising operation, the motor 59 may be controlled by the switch 82, which may be manually operated at the outside of the cabinet so that after the valve 55 has been turned to position to connect the pump with the interior of the standard 14, the operator may start the motor so as to raise the dish rack and, at the end of the operation, stop the motor to hold the dish rack in raised position during the loading of dishes thereinto.

Mounted within the cabinet and between the front wall thereof and the front wall of the tank or tub 11 is a soap dispenser comprising a container 84 having a swinging door 85 at the front of the cabinet, which may be swung outwardly and permit the filling of the container. In its lower end, the walls of the container converge as shown at 86 and 87 (Fig. 12), and in this portion of the container is mounted a slide 88 having an opening 89 therein into which opening the soap descends when the slide is in the position as shown in Fig. 12, the soap being contained therein by the bottom 90 of the container itself. The lower portion of the container is provided with a laterally offset chute 91 with which the opening 89 is adapted to register when the slide 88 is shifted to the right from the positions shown in Figs. 12 and 13. The slide is provided with a portion 92 extending beyond the container, to which is connected a spring 93 suitably tensioned to normally hold the slide in closed position or in the position shown in Fig. 12. A lever 94 pivoted at 95 is provided at its lower end with a slot 96 embracing a pin 97 upon the portion 92 of the slide, so that when the lever is oscillated, the contents of the opening 89 in the slide drop through the chute 91, which as shown in Fig. 11 communicates with the tub 11 through the opening 98. When the slide is moved to the discharging position just described, the bottom of the container will be closed by the part 99 of the slide so as to retain the remainder of the contents of the container in the latter until the slide is returned by the spring 93 and again permits a quantity of soap to descend into the opening 89. This portion 89 of the slide thereby constitutes a measuring device to deliver a measured quantity of soap to the tank of the machine.

The control mechanism is shown more particularly in Figs. 1 to 5 of the drawing and comprises a disk-like member 100 secured to a shaft 101 rotatably mounted in the control panel 13 and extending without the case or cabinet 10 where, upon its extended end, is secured a control knob 102. The shaft passes through a sleeve 104, and a compression spring 105 is mounted between the end wall of this sleeve and a washer 106 mounted on the shaft and held in place by

the pin 107. With this arrangement the shaft may move inwardly against the tension of spring 105, but will be normally held in the position illustrated in Fig. 5. The inner face of the sleeve 104 is provided with recesses 108 at intervals of 90°, these recesses being adapted to receive a rib 109 on the hub 110 of the disk 100 so that the disk will be yieldably held in one of four positions about its axis of rotation. It will be understood that the rib 109 is permitted to move out of the recess 108 against the tension of spring 105 in order to permit free rotation of the disk, except for the tendency of the latter to be held at one of the four stations corresponding to one of the four steps in the operation of the device.

Secured at diametrically opposite points to the disk 100 are outwardly projecting arms 112 and 113 having long and short rearwardly extending pins 114 and 115 carried thereby. It will be noted from Fig. 3 that pin 114 is adapted to lie below both of the arms or levers 33 and 38^a, while the pin 115 is not of sufficient length to reach the lever 38^a and, therefore, will operate the lever 38 only when the control disk 100 is rotated.

The control disk is also provided with a second pair of rearwardly extending pins 116 and 117 located at points substantially 90° apart on the disks 100, which pins lie below and are adapted to actuate a lever 118 pivoted at 119 and normally urged downwardly by a spring 120. The lever 118 has mounted thereon a mercury switch 121 of the usual form, this switch, when tipped by the oscillation of the lever 118, making contact to supply current to the motor 59 to set this motor in operation, whereby the starting of the motor will be effected automatically upon the turning of the control disk 100. It may here be stated that the manually operated switch 82, which also controls the motor to effect the raising of the rack 16, will be connected to the motor in parallel with the switch 121 so that the operation of either of these switches will start the motor independently of the other.

The disk 100 is also provided with a stud 122 designed to contact the lever 94 once during each revolution and operate the slide 88 to deliver a predetermined quantity of soap to the container for the washing operation, this engagement taking place at the first movement of the controlling disk from its "off" position. Also connected to the stud 122 is an extensible spring 123 secured at its other end to a link 124. The other end of this link is secured to the lever 24, which operates the drain valve 22. The spring 123 provides an extensible connection between the disk 100 and the drain valve so that after the drain valve is closed, the disk can be rotated through its further phases of operation and the drain valve held in closed position.

Also leading from the bottom of the tank 11 is an overflow drain 126 which communicates with the pipe 71. It will be noted from Fig. 1 that the pipe 126 is reversely curved to extend above the bottom of the tank so that it empties into the pipe 71 at a point above the bottom of the tank in order to maintain a certain level of water in the tank. The pipe 71 is continued upwardly beyond the pipe 126 and is left open at the top, as shown at 127, so as to prevent a syphoning action of the water from the tub when the over-flow drain becomes operative, which it will do during the rinsing operation, as will be hereinafter described.

The operation of my device is as follows: Referring particularly to Figs. 7 to 10, the

"off" position of the parts is that shown in Fig. 7 in which the drain valve is held in open position by the spring 27, and the levers 38 and 38^a are held down by the springs 39 and 39^a so that the hot and cold water valves are closed and the slide 88 of the soap container is in the position as shown in Fig. 12. The disk 100 is then given a quarter turn in a clockwise direction to the "fill" position, shown in Fig. 8. In this position the drain valve is closed by the link 124. The valve levers 38 and 38^a are raised by the pin 114 to admit hot and cold water into the tub. During this movement the slide 88 is moved to the right from the position shown in Fig. 12 to deliver a measured quantity of soap to the tank so that during this operation the drain valve is closed and hot and cold water and soap are admitted to the tank.

The disk 100 is then turned through a further quarter revolution when a sufficient amount of water has been admitted to the tank, which is the washing or operating position of the parts shown in Fig. 9. This movement is permitted by the extension of the spring 123, the drain valve still being held closed. During this movement, the valve levers 38 and 38^a are released and drawn to closed position by their springs 39 and 39^a, thus shutting off the admission of water. The pin 117 picks up the arm 118 and raises this arm against the tension of the spring 120 to tilt the switch 121 to start the motor 59. The valve 55 will be assumed to be in the position shown in Fig. 1, and it will be seen that water will be drawn from the tank by means of the pipe 62 from well 21 and will be forced through pipes 57 and 53 through the rotating spray head 59 to spray this water forcibly upon the dishes in the tank and effect rotation of the spray head by the reaction of the jets of water issuing therefrom.

When the dishes are cleansed, the disk 100 is moved through a further angle of 90° to the position shown in Fig. 10 of the drawings, which is the "rinse" position. The drain valve is still retained in closed position and the pin 115 engages and raises the valve lever arm 38 thus admitting hot water to the tank, the cold water valve remaining in closed position. The switch arm 113 will be during this movement momentarily released by the pin 117 but will be picked up by the pin 116 and will, therefore, continue the operation of the motor to maintain an effective spray upon the dishes, as previously described, to rinse them thoroughly. During the admission of the hot rinse water to the tank, the level of the water therein will be raised sufficiently to flow out of the drain 126 and pipe 71. As the connection of the pipe 126 is made at the very bottom of the tank, this will carry off to a large extent the water used during the washing operation and the dishes will be rinsed in the fresh hot water which is permitted to enter.

When the rinsing operation is complete, the disk 100 is turned to the starting or "off" position shown in Fig. 7. Both hot and cold water valves will then be closed, the action of the motor will be stopped, and the drain valve will be opened to permit the draining of the tub.

By means of the lever 67, the valves 55 may now be rotated through the link 64, and this rotation will serve to connect the pipe 60 to a pipe 128 leading to the cold water supply. Also the pipe 57, which is the outlet of the pump, will be connected through the port 56 to the pipe 74 leading to the hydraulic lift. The motor may now be started through the manually operated switch 82 to force water into the standard 14 and thus raise

the dish rack 16 to an elevated position so that the dishes may readily be removed. When it has reached this position, the motor will be stopped by the switch 82, and the pressure in the tubular member 15 will hold the rack in elevated position. If, however, the operator forgets to operate the switch 82 for a moment, the valve 75 will be raised from its seat and permit the water in the member 15 to be vented through the pipe 71 so that the elevation of the dish rack will be limited by the length of the chain 76.

When the dish rack has been reloaded, the valve 55 is rotated to its original position, that shown in Fig. 1, wherein the pipe 74 is connected with the pipe 81 leading to the drain 20 so as to permit the venting of the water from the tubular member 15 and allow the dish rack to descend under the influence of gravity. The parts are now in a position for a subsequent cycle of operations.

It will be noted that during the admission of water into the tub for the washing operation and also for the rinsing operation, the water sprays into the tub through the spray openings 47 and 48, which openings are in the form of narrow slots to permit the effective spraying of water over the tops of the dishes to give them a preliminary cleansing; and that during the washing and rinsing operation, the rotation of the spray head jets will insure that all of the surfaces of the dishes will be effectively cleansed by the spray jet which issues therefrom.

In Fig. 14 of the drawings I have shown a modified form of hydraulically operated lifting means 35 for the dish rack 16. In this instance the raising mechanism is placed below the dish rack so that it will not be disposed within the tub above the rack, but will be entirely below the latter.

A tubular member 130 projects upwardly 40 through the bottom of the tub and through the rotary spray head 50. Within the member 130 is a piston 131 having a packing 132 making tight contact with the tubular member 130. The piston carries at its lower end a rod 133 which extends downwardly from the connection 73 and has an abutment 134 mounted adjustably upon its lower end. Upon the upper end of the piston 131 is supported the rack 16, so that when water under pressure is admitted to the tube 130 below the piston through the connection 73 and pipe 74, the piston will be raised and elevate the dish rack.

In this instance, the motor 59, which drives the pump 58, is controlled by a pair of tiltable mercury switches 135 and 136, which are connected in series so that both switches must be closed to effect actuation of the motor. The switch 135 is mounted on a link 137 pivoted at 138, the free end of this link extending to a point adjacent the controlling member 64, so that it will be engaged by an abutment 139 on this lever. It will be seen, therefore, that when the lever 64 is raised to rotate the valve 55 and connect the pipe 74 with the outlet 57 of the pump 58, the link 137 will be raised about its pivot and therefore close the contacts of the switch 135. The normal position of the switch 136 is shown in Fig. 14, and in this position the contacts are closed so that upon actuation of the valve 55 by the member 64, the motor will automatically be set into operation.

The switch 136 is pivotally mounted on a lever 140 pivoted at 141 to an arm 142, which may be secured to the connection 73. The lever 140 is provided with a stop 143 engaging the arm 142 to limit the downward movement of the free end

of the lever under gravity, which force normally maintains the lever in the position shown in the drawings. The lever 140 is provided with a finger 144 extending to a point adjacent the rod 133 to be engaged by the abutment 134 when the dish rack 16 is raised by the piston 131 and reaches a point adjacent the limit of its upward movement. It will be seen, therefore, that further upward movement of the rod 133 will swing the lever 140 about its pivot 141 and thus break the contacts of the switch 136 to stop the motor. Therefore, the motor will be automatically stopped when the dish rack is raised to a predetermined elevated position.

It will be seen, therefore, that when the dish rack is in elevated position, the switch 135 is closed and the switch 136 opened. When the member 64 is again operated to return the valve to its original position (as shown in Fig. 14), the link 137 will drop and again break the contacts of the switch 135. In this position, the connection 73 is in communication with the drain pipe 20 and the dish rack and piston 131 will descend. With the descent of the rack, the lever 140 will again drop due to the action of gravity and close the switch 136. The motor 59 will not be started, however, due to the fact that the switch 135 is open. However, the parts are in position for again starting the motor when the member 64 is again raised to rotate the valve 55.

It will be understood that the control of the motor 59 by the switches 135 and 136, automatically operated upon raising and lowering of the dish rack 16, is employed in addition to the control of the motor by the mercury switch 121 to effect the washing and rinsing of the dishes.

While I have shown and described a preferred embodiment of my invention, it will be understood that it is not to be limited to all of the details shown, but is capable of modification and variation within the spirit of the invention and within the scope of the claims.

What I claim is:

1. A dishwashing machine comprising a tub, a standard projecting upwardly from the bottom of the tub, a dish rack, means for supporting the dish rack on said standard in a position spaced from the bottom of the tub, a hollow sprayer

head, means on the bottom of the tub for supporting said sprayer head for rotation about said standard, and means to draw water from the tub and force it through said sprayer head toward the dish rack.

2. A dishwashing machine comprising a tub, a standard projecting upwardly from the bottom of the tub, a dish rack, means for supporting the dish rack on said standard in a position spaced from the bottom of the tub, a hollow sprayer head, means on the bottom of the tub for supporting said sprayer head for rotation about said standard, and means to draw water from the tub and force it through said sprayer head toward the dish rack, said dish rack being slidably mounted on said standard.

LAWRENCE A. LOEB.
